UNITED STATES PATENT OFFICE

1,939,902

NONLINEAR VARIABLE RESISTANCE ELEMENT

John Kaul, Cincinnati, Ohio, assignor to The Crosley Radio Corporation, Cincinnati, Ohio, a corporation of Ohio

Application August 6, 1928. Serial No. 297,843

10 Claims. (Cl. 201—55)

My invention relates to variable resistance, the resistance of which varies as some function of the length of the resistance element.

My object is more particularly to provide a resistance element in which the arrangement is such that the proportionate change of resistance for a given amount of movement of the slider element or between taps at a given distance from the line side of the resistance will have a prearranged value.

The invention consists essentially in modifying the linear resistance of a wire or other resistance element by plating thereon the same or a different metal in a prearranged manner. It also consists in so plating that a tapered formation of the deposit on the linear resistance element will give a difference of total resistance per unit of length which changes in a prearranged gradual manner, thus cooperating with a moving element or slider so that a given movement of the slider will, at some parts of the resistance, effect less of a change than at other parts, which change can be made gradual and uniformly so.

I accomplish my objects by that certain structure of which an example will be hereinafter specifically described, and the novelty of which will be covered in the appended claims.

In the drawing:—

Figure 1 is a diagram of a plating step.

Figure 2 is a diagram illustrating a tapered deposit on a resistance wire.

Figure 3 is a diagram showing a like deposit made on a flat wound spiral.

Figure 4 is a plan view of a simple rheostat built in accordance with my invention.

Figure 5 is a side elevation of such a rheostat.

Figure 6 is a sectional view of an alternative plating tank in operation.

It will be understood that my invention applies to strips, wire, or other resistance elements, which may be straight or wound at the time that the electro-deposit is built up thereon.

I have shown in Figure 1 a diagram of an electrolytic bath 1 in which are electrodes, say of copper, as at 2. A coil of resistance wire 3 is inserted at one end into the bath, and coupled with a conductor 4. The copper electrodes are coupled to a conductor 5.

When plating is carried on in the manner indicated by passing a current through the bath, copper will be deposited upon the resistance wire. The deposit will, however, be heaviest at the end of the wire nearest to the attachment thereof to the conductor within the electrolyte, and will taper off upwardly (in the instance shown).

By controlling the time of deposition I can provide a fairly heavy coating of copper, in the example given, on the resistance wire at one end which tapers off to a mere blush at the other end, whereupon the resistance element is withdrawn 60 from the bath.

The manner of forming my special resistance member depends upon the initial resistance of the member itself. As is well known, when an electrolytic cell containing electrolyte and anodes is used 65 for plating a cathode of low resistance, if the throwing power of the solution is satisfactory, a plating over the surface of the cathode may be obtained which to all intents and purposes is uniform. This sort of plating is what is ordinarily 70 desired, but when plating is attempted on an element of high resistance, to which contact is made only at one end, there will be a shading off of the current density passing into the electrolyte and through it to the anodes from varying portions of 75 the cathode depending on the resistance of the portion of the cathode itself lying between the current connection and any given point in the cathode. If the cathode consists therefore of a length of wire (which is usually already wound 80 upon an insulating support), the current density at the end of it next the current connection which is effective for the electrolyte plating action will be comparatively large, while it will shade off rapidly from that point toward the other end of the 85 cathode. Thus heavy deposits are obtained at the part adjacent the current connection and the deposit will shade off toward the other end where, depending upon the time allowed for the electro-depositing action, it may be very small indeed or 90 practically non-existent. A logarithmic resistance curve may be built up by means of this mode of deposit.

Considering the resistance wire as a straight strand, I have indicated in Figure 2 the nature of the deposit, which is quite thick, at 6, and tapers gradually and proportionately in a linear manner down to the bare resistance element which may be said to be uncoated at 7.

In Figure 3 I show the resistance element in a coil wherein the copper deposit is heaviest at the end 8, and tapers down to a mere blush, after 100 which the resistance wire is uncoated.

Instead of plating on a wound resistance, I can plate on a bare wire, or I can plate on the wire in one wound condition and then re-wind it into another. By attaching conductors to various parts of a wire, wound or straight, I can again 105 control the nature of the deposit, tapering it, or 110

controlling it so that I vary the thickness and the taper at will.

It will be understood that I can use any desired conductive resistance element, and any desired metal to plate thereon, which adds or detracts from the resistance, and tapers or not as I see fit.

In particular my process is useful in obtaining a truly and proportionately tapered deposit, thereby gaining cheaply an effect which is quite expensive to obtain otherwise, requiring as it does a complicated mechanical arrangement whereby for a given movement of the operating element, a differential movement is applied to the actual contact member or slider, which engages the resistance element or taps taken therefrom.

In Figure 4 is shown a rheostat in which the flat wound resistance coil 8 is laid around a suitable cylindrical barrel or housing which supports at its axis an arm 9. The arm has a slider 10 thereon which wipes over the resistance element.

So far as I am aware the principle of graduated deposits upon a high resistance cathode has not hitherto been used to produce resistance elements which do not vary in a linear manner.

I desire it to be understood that my invention is not therefore limited to plating upon wire or strands of resistance elements but is equally adapted to strips, or to formed integral resistance elements. Thus a resistance element comprising

a single thin bar of high resistance material may be treated in a similar manner. If it be of metal it may be plated with the same metal so as to decrease the resistance at one end thereof by a single thickening.

Or it may be plated with a different metal so as to gain different effects. Again if not of metal at all, it may be plated with metal so as to decrease its resistance at one end. The chief advantages of my invention are two: first, that it gives an extremely quick and easy method of securing a non-linear resistance, which has been made in the past only with great difficulty and usually by the piecing together of various materials of differing resistance. Second, I am able to produce resistance elements which do not have

a linear variation but which nevertheless can be varied smoothly since there are no quick jumps in my element from an area of high resistance to an area of considerably lower resistance.

I have shown in Figure 1 a plating step in which the resistance member is not entirely immersed in the electrolyte. This is convenient where no deposit is desired at one end of the element, but the plating can also be carried on as shown in Figure 6 where the entire element is immersed, and here the quantity of deposit on the end of the element furthest from the current connection will be proportioned to the resistance of the element, the electromotive force impressed upon it, and the length of time it remains in the electrolyte.

Suitable conductors and suitable insulation, as will be understood without illustration, will carry a line connection to one end of the resistance element, the load connection being made to the slider. Otherwise, as illustrated, the resistance element may be connected across a line, such as for example, the antenna circuit of a radio receiver, using terminals 11 and 12, insulated from the frame of the structure, and the slider may be metallic and contact with the frame of the structure, and connected, say, to a point of zero or ground potential in the radio receiver.

Having thus described my invention, what I claim as new and desire to secure by Letters

75 Patent, is:—

1. A linear resistance element having thereon a tapered deposit of additional metal.

2. A coiled linear conductor to be used as a resistance, certain coils of said conductor having a coating of additional conductive material and certain of said coils having on them successively more conductive material than certain preceding coils.

3. A conductor to be used in providing a variable resistance comprising an electrically conductive base element of high resistance proportions and an electrically conductive coating on and electrically continuous with said base element, having a plurality of variations in electrical conductivity at intervals of its length, whereby the resistance of the conductor per unit of length is a modification of the inherent resistance of the base element per unit of length.

4. A conductor to be used in providing a variable resistance comprising an electrically conductive base element of high resistance proportions and an electrically conductive coating on and electrically continuous with said base element, having a plurality of variations in thickness at intervals of its length.

5. A conductor to be used in providing a variable resistance comprising a metal base element of high resistance proportions and a metal coating on and electrically continuous with said base element, having a plurality of variations in thickness at intervals of its length.

6. A variable resistance device comprising a metal wire and a contact element to make electrical contact therewith at different intervals of its length, in which the wire has thereon a coating of metal electrically continuous therewith and so disposed thereon that the electrical conductivity of said conductor varies at said different intervals of its length.

7. A coiled electrical conductor having thereon a coating of conductive material electrically continuous therewith, in different amounts on different coils thereof so as to afford a plurality of variations of electrical conductivity of said conductor from one coil to another.

8. A coiled metal wire having on one of its coils a coating of metal electrically continuous therewith and having on another one of its coils a coating of metal electrically continuous therewith, greater in amount than the coating on the one coil, so as to vary the electrical conductivity of said conductor from one coil to the other, and an electrical contact element movable from one coil to the other.

9. A coiled electrical conductor having a coating of conductive material thereon, electrically continuous therewith, on a number of coils less than the full number of coils thereof varying in amount on the several coils, the other coils being devoid of coating, whereby there is a variation of electrical conductivity from coil to coil.

10. A variable resistance device comprising a conductor and a contact element to make electrical contact therewith at different intervals of its length, in which a portion of the conductor with which the contact element makes contact has a coating of conductive material thereon electrically continuous therewith varying in amount at intervals of the length of said portion, and another portion of said conductor with which said contact element makes contact is devoid of coating, so as to afford a plurality of variations of electrical conductivity of the conductor in successive portions with which the contact element makes contact.
